US00D916867S

(12) **United States Design Patent** (10) Patent No.: **US D916,867 S**
(45) Date of Patent: **** Apr. 20, 2021**

(54) **DISPLAY SCREEN OR PORTION THEREOF WITH GRAPHICAL USER INTERFACE**

(71) Applicant: **Apple Inc.**, Cupertino, CA (US)

(72) Inventors: **Taylor Gerard Carrigan**, San Francisco, CA (US); **Patrick Lee Coffman**, San Francisco, CA (US); **Thalia Echevarria Fiol**, Cupertino, CA (US); **Christopher P. Foss**, San Francisco, CA (US); **Bon Min**, Seoul (KR); **Eric Lance Wilson**, San Jose, CA (US)

(73) Assignee: **Apple Inc.**, Cupertino, CA (US)

(**) Term: **15 Years**

(21) Appl. No.: **29/680,496**

(22) Filed: **Feb. 15, 2019**

(51) LOC (13) Cl. **14-04**

(52) U.S. Cl.

USPC **D14/488**

(58) **Field of Classification Search**

(57) **CLAIM**

The ornamental design for a display screen or portion thereof with graphical user interface, as shown and described.

DESCRIPTION

The sole FIGURE shows a front view of a display screen or portion thereof with graphical user interface showing the claimed design.

The peripheral dashed broken lines illustrate a display screen or portion thereof, and form no part of the claimed design.

1 Claim, 1 Drawing Sheet
